UNITED STATES PATENT OFFICE.

LE ROY W. FAIRCHILD, OF NEW YORK, N. Y.

DESIGN FOR A PENCIL-CASE.

SPECIFICATION forming part of Design No. 12,001, dated October 26, 1880.

Application filed June 26, 1880. Term of patent 7 years.

To all whom it may concern:

Be it known that I, LE ROY W. FAIRCHILD, a citizen of the United States, residing at the city, county, and State of New York, have invented and produced a new and original Design for Pencil or other Small Implement Cases, of which the following is a specification, reference being had to the photographic illustrations forming a part thereof.

Figure 1 is a side elevation of my newly-designed case; and Fig. 2 is a side elevation of the same, with pencil extended for writing, these two views being necessary to illustrate my design.

The case is substantially in the form of a lantern, with wire guards, bail-handle, chimney at the top, and oil-reservoir and foot at the bottom.

A represents the body of the case, spheroidal in form, to imitate the transparent body of a lantern.

B represents a collar, into which the body A is inserted and attached in ogee form, surrounded by the dome or head C, on which may be represented perforations, the said collar and head being made to imitate the top of a lantern-frame in which the body is set with its chimney and perforations for draft.

D is a trumpet-shaped end of the case, made to represent the foot or part of a lantern-frame in which the lamp is set.

E is a circular wire with an end loosely inserted in either side of the collar B, the same imitating the handle of a lantern.

a a a represent a series of wires in curvilinear form connecting at equal intervals around their circumferences the collar B and the end D at points near where said collar and end are respectively joined to the body A.

b b b represent circular wires equidistant from the collar B and end D, and from each other, inclosing horizontally the curvilinear wires *a a a*. The case has a circular hole or opening in the end at *c*. The said curvilinear and circular wires imitate and represent the wire guards of a lantern by which the transparent body is protected.

The case may be made of metal, of a single color or variegated; but I do not consider color an element of my design.

50

I claim—

The design for a pencil or other small implement case, the same consisting of the body A, collar B, head C, suspending-ring E, end D, curvilinear wires *a a a*, &c., and circular wires *b b b*, and hole *c*, substantially as shown and described.

LE ROY W. FAIRCHILD.
